ABSTRACT OF THE DISCLOSURE

This invention relates to new chemical compounds which are phosphate esters and phosphonate esters having three organic radicals at least one of which is the cyclopropyl radical and the other organic radicals of which are the cyclopropyl radical, the phenyl radical, or the tolyl radical.

These new chemical compounds are useful for thermally 20 stable fire resistant hydraulic fluids, especially for aircraft, either alone or admixed with other additives.

These compounds particularly include the following:

(1) Phosphate esters

Tricyclopropyl phosphate 25
Dicyclopropyl phenyl phosphate
Monocyclopropyl diphenyl phosphate
Dicyclopropyl tolyl phosphate
Monocyclopropyl ditolyl phosphate
Monocyclopropyl tolyl phenyl phosphate

(2) Phosphonate esters

Dicyclopropyl cyclopropane phosphonate
Dicyclopropyl benzene phosphonate
Diphenyl cyclopropane phosphonate
Dicyclopropyl toluene phosphonate
Ditolyl cyclopropane phosphonate
Monocyclopropyl tolyl benzene phosphonate
Monocyclopropyl phenyl toluene phosphonate

The phosphonate esters particularly include the following:

Dicyclopropyl cyclopropane phosphonate

Herein CP stands for the cyclopropyl radical.

Diphenyl cyclopropane phosphonate

Herein Ph stands for the phenyl radical.

Dimetatolyl cyclopropane phosphonate

Herein T stands for the tolyl radical and generically 70 designates ortho, meta, and para tolyl and mixtures thereof.

2

Cyclopropyl metatolyl cyclopropane phosphonate

Herein Tm designates the metatolyl radical.

Cyclopropyl phenyl cyclopropane phosphonate

Dicyclopropyl benzene phosphonate

Dicyclopropyl toluene phosphonate

Cyclopropyl phenyl benzene phosphonate

Cyclopropyl metatolyl benzene phosphonate

Cyclopropyl tolyl toluene phosphonate

Cyclopropyl phenyl toluene phosphonate

Tolyl phenyl cyclopropane phosphonate

Each of these new foregoing chemical compounds can be made by the same methods used for making the corresponding phosphates and phosphonates where the propyl radical is used instead of the cyclopropyl radical. The methods of making the corresponding phosphates and phosphonates with the propyl radical are known to those skilled in the art, and with the disclosure herein those skilled in the art to which my invention appertains will be able to make and use the new chemical compounds of my invention.

The preparation of the known phosphate esters and phosphonate esters having the propyl radical instead of the cyclopropyl radical of my invention is disclosed in the books entitled "Introduction to Hydraulic Fluids" by Roger E. Hatton, published by Rheingold Publishing Corporation and "Organic-Phosphorous Compounds" by G. M. Kosolopoff, published by John Wiley and Sons, and numerous other publications and issued patents. The particular relevant disclosure in the book entitled "Introduction to Hydraulic Fluids" appears on pages 190 through 195.

Even though those skilled in the art will be able to prepare and use the new chemical compounds of my invention, there is given below examples of these compounds and their preparation.

EXAMPLE 1

Tricyclopropyl phosphate

3.5 mols of cyclopropyl alcohol are added dropwise with stirring to one mol of phosphorus oxychloride (POCl_3) at 25-35° C. The temperature is slowly brought up to about 65° C. and the pressure is slowly reduced to 50 mm./Hg with stirring to remove hydrogen chloride. The mixture is then distilled and tricyclopropyl phosphate is collected.

EXAMPLE 2

Tricyclopropyl phosphate

To 5 mols of cyclopropanol, three mols of freshly cut metallic sodium are added in small cubes about $\frac{1}{4}$ " with stirring and maintaining the temperature between 25 and 40° C. When reaction is complete as evidenced by cessation of bubbling, one mol of phosphorus oxychloride (POCl_3) is added dropwise with stirring while maintaining the temperature at about 25-50° C. The reaction mixture is filtered to remove the precipitated sodium chloride and the filtrate is distilled and tricyclopropyl phosphate is collected.

EXAMPLE 3

Dicyclopropyl phenyl phosphate

Two mols of cyclopropanol are added dropwise with stirring to one mol of POCl_3 at 25-35° C. The temperature is slowly brought up to about 65° C. and the pressure is slowly reduced to 50 mm./Hg to remove hydrogen chloride. Without further purification this mixture is added dropwise at 0-5° C. to a saturated solution of one mol of phenol in one mol of sodium hydroxide with good stirring. The mixture is allowed to rise in temperature to 25° C. with continued stirring. The resulting mixture is washed, dried and distilled to separate out the desired water insoluble dicyclopropyl phenyl phosphate.

EXAMPLE 4

Dicyclopropyl tolyl phosphate

Two mols of cyclopropanol are added dropwise with stirring to one mol of POCl_3 at 25-35° C. The temperature is slowly brought up to about 65° C. and the pressure is slowly reduced to 50 mm./Hg to remove hydrogen chloride. Without further purification this mixture is added dropwise at 0-5° C. to a saturated solution of one mol of metacresol in one mol of sodium hydroxide with good stirring. The mixture is allowed to rise in temperature to 25° C. with continued stirring. The resulting mixture is washed, dried and distilled to separate out the desired water insoluble dicyclopropyl metatolyl phosphate.

EXAMPLE 5

Monocyclopropyl diphenyl phosphate

One mol of cyclopropanol is added dropwise with stirring to one mol of POCl_3 at 25-35° C. The temperature is slowly brought up to about 65° C. and the pressure is

slowly reduced to 50 mm./Hg to remove hydrogen chloride. Without further purification this mixture is added dropwise at 0-5° C. to a saturated solution of two mols of phenol in two mols of NaOH with good stirring. The mixture is allowed to rise in temperature to 25° C. with continued stirring. The resulting mixture is washed, dried and distilled to separate out the desired water insoluble monocyclopropyl diphenyl phosphate.

EXAMPLE 6

Monocyclopropyl paratolyl phosphate

One mol of cyclopropanol is added dropwise with stirring to one mol of POCl_3 at 25-35° C. The temperature is slowly brought up to about 65° C. and the pressure is slowly reduced to 50 mm./Hg to remove hydrogen chloride. Without further purification this mixture is added dropwise at 0-5° C. to a saturated solution of two mols of paracresol in two mols of NaOH with good stirring. The mixture is allowed to rise in temperature to 25° C. with continued stirring. The resulting mixture is washed, dried and distilled to separate out the desired water insoluble monocyclopropyl paratolyl phosphate.

EXAMPLE 7

Monocyclopropyl phenyl tolyl phosphate

One mol of cyclopropanol is added dropwise with stirring to one mol of POCl_3 at 25-35° C. The temperature is slowly brought up to about 65° C. and the pressure is slowly reduced to 50 mm./Hg to remove hydrogen chloride. Without further purification this mixture is added dropwise at 0-5° C. to a saturated solution of one mol of phenol in one mol of sodium hydroxide with good stirring. The mixture is allowed to rise in temperature to 25° C. with continued stirring. The mixture is filtered and the filtrate is added dropwise, without further purification, at 0-5° C. to a saturated solution of one mol of metacresol in one mol of NaOH with good stirring. The mixture is allowed to rise in temperature with continued stirring. The resulting mixture is washed, dried and distilled to separate out the desired water insoluble monocyclopropyl phenyl metatolyl phosphate.

EXAMPLE 8

Dicyclopropyl cyclopropane phosphonate

Three mols of cyclopropanol are added dropwise with stirring to one mol of cyclopropane phosphorus oxydichloride, at 25-35° C. The temperature is slowly brought up to about 65° C. and the pressure is slowly reduced to 50 mm./Hg with stirring to remove hydrogen chloride. The mixture is then distilled and dicyclopropyl cyclopropane phosphonate is collected.

EXAMPLE 9

Diphenyl cyclopropane phosphonate

Three mols of phenol are added dropwise with stirring to one mol of cyclopropane phosphorus oxydichloride at 25-35° C. The temperature is slowly brought up to about 65° C. and the pressure is slowly reduced to 50 mm./Hg with stirring to remove hydrogen chloride. The mixture is then distilled and diphenyl cyclopropane phosphonate is collected.

EXAMPLE 10

Dimetatolyl cyclopropane phosphonate

Three mols of metacresol are added dropwise with stirring to one mol of cyclopropane phosphorus oxydichloride at 25-35° C. The temperature is slowly brought up to about 65° C. and the pressure is slowly reduced to 50 mm./Hg with stirring to remove hydrogen chloride. The mixture is then distilled and dimetatolyl cyclopropane phosphonate is collected.

EXAMPLE 11

Cyclopropyl metatolyl cyclopropane phosphonate

One mol of cyclopropanol is added dropwise with stirring to one mol of cyclopropane phosphorus oxydichloride at 25-35° C. The temperature is slowly brought up to about 65° C. and the pressure is slowly reduced to 50 mm./Hg with stirring to remove hydrogen chloride. Without further purification this mixture is added dropwise at 0-5° C. to a saturated solution of one mol of metacresol in one mol of sodium hydroxide with good stirring. The mixture is allowed to rise in temperature to 25° C. with continued stirring. The resulting mixture is washed, dried and distilled to separate out the desired water insoluble cyclopropyl metatolyl cyclopropane phosphonate. 15

EXAMPLE 12

Cyclopropyl phenyl cyclopropane phosphonate

One mol of cyclopropanol is added dropwise with stirring to one mol of cyclopropane phosphorus oxydichloride at 25-35° C. The temperature is slowly brought up to about 65° C. and the pressure is slowly reduced to 50 mm./Hg with stirring to remove hydrogen chloride. Without further purification this mixture is added dropwise at 0-5° C. to a saturated solution of one mol of phenol in one mol of sodium hydroxide with good stirring. The mixture is allowed to rise in temperature to 25° C. with continued stirring. The resulting mixture is washed, dried and distilled to separate out the desired water insoluble cyclopropyl phenyl cyclopropane phosphonate. 20

EXAMPLE 13

Dicyclopropyl benzene phosphonate

Three mols of cyclopropanol are added dropwise with stirring to one mol of benzene phenyl phosphorus oxydichloride at 25-35° C. The temperature is slowly brought up to about 65° C. and the pressure is slowly reduced to 50 mm./Hg with stirring to remove hydrogen chloride. The mixture is then distilled and dicyclopropyl benzene phosphonate is collected. 35

EXAMPLE 14

Dicyclopropyl toluene phosphonate

Three mols of cyclopropanol are added dropwise with stirring to one mol of metatoluene phosphorus oxydichloride at 25-35° C. The temperature is slowly brought up to about 65° C. and the pressure is slowly reduced to 50 mm./Hg with stirring to remove hydrogen chloride. The mixture is then distilled and dicyclopropyl toluene phosphonate is collected. 45

EXAMPLE 15

Cyclopropyl phenyl benzene phosphonate

One mol of cyclopropanol is added dropwise with stirring to one mol of benzene phosphorus oxydichloride at 25-35° C. The temperature is slowly brought up to about 65° C. and the pressure is slowly reduced to 50 mm./Hg with stirring to remove hydrogen chloride. Without further purification this mixture is added dropwise at 0-5° C. to a saturated solution of one mol of phenol in one mol of sodium hydroxide with good stirring. The mixture is allowed to rise in temperature to 25° C. with continued stirring. The mixture is washed, dried and distilled and cyclopropyl phenyl benzene phosphonate is collected. 50

EXAMPLE 16

Cyclopropyl metatolyl benzene phosphonate

One mol of cyclopropanol is added dropwise with stirring to one mol of benzene phosphorus oxydichloride at 25-35° C. The temperature is slowly brought up to about 65° C. and the pressure is slowly reduced to 50 mm./Hg with stirring to remove hydrogen chloride. Without further 55

purification this mixture is added dropwise at 0-5° C. to a saturated solution of one mol of metacresol in one mol of sodium hydroxide with good stirring. The mixture is allowed to rise in temperature to 25° C. with continued stirring. The mixture is washed, dried and distilled and cyclopropyl metatolyl benzene phosphonate is collected. 60

EXAMPLE 17

Cyclopropyl tolyl toluene phosphonate

One mol of cyclopropanol is added dropwise with stirring to one mol of metatoluene phosphorus oxydichloride at 25-35° C. The temperature is slowly brought up to about 65° C. and the pressure is slowly reduced to 50 mm./Hg with stirring to remove hydrogen chloride. Without further purification this mixture is added dropwise at 0-5° C. to a saturated solution of one mol of metacresol in one mol of sodium hydroxide with good stirring. This mixture is allowed to rise in temperature to 25° C. with continued stirring. The mixture is washed, dried and distilled and cyclopropyl tolyl toluene phosphonate is collected. 10

EXAMPLE 18

Cyclopropyl phenyl toluene phosphonate

One mol of cyclopropanol is added dropwise with stirring to one mol of metatoluene phosphorus oxydichloride at 25-35° C. The temperature is slowly brought up to about 65° C. and the pressure is slowly reduced to 50 mm./Hg with stirring to remove hydrogen chloride. Without further purification this mixture is added dropwise at 0-5° C. to a saturated solution of one mol of phenol in one mol of sodium hydroxide with good stirring. This mixture is allowed to rise in temperature to 25° C. with continued stirring. The mixture is washed, dried and distilled and cyclopropyl phenyl toluene phosphonate is collected. 20

EXAMPLE 19

Tolyl phenyl cyclopropane phosphonate

One mol of metacresol is added dropwise with stirring to one mol of cyclopropane phosphorus oxydichloride at 25-35° C. The temperature is slowly brought up to about 65° C. and the pressure is slowly reduced to 50 mm./Hg with stirring to remove hydrogen chloride. Without further purification this mixture is added dropwise at 0-5° C. to a saturated solution of one mol of phenol in one mol of sodium hydroxide with good stirring. This mixture is allowed to rise in temperature to 25° C. with continued stirring. The mixture is washed, dried and distilled and tolyl phenyl cyclopropane phosphonate is collected. 30

The compositions of my invention have high thermal stability apparently due to the presence of the cyclopropyl radical, high fire resistance, good lubricity, especially hydrodynamic lubricity, good boundary lubrication and good anti-wear, have ability to lubricate moving parts, particularly steel on steel, good viscosity and viscosity-temperature properties, and are readily admixed with many additives. 40

It will be understood that the specific embodiments of my invention described above are intended to illustrate and exemplify my invention and are not necessarily intended as a limitation thereon and that modifications of my invention may be made. 50

I claim:

1. The phosphate and phosphonate esters represented by the formula $(R_1R_2R_3)O_2O_xPO$ in which x may be one or zero, R_1 is cyclopropyl, and R_2 and R_3 are cyclopropyl, phenyl or tolyl.
2. The chemical compound as defined in claim 1 which is tricyclopropyl phosphate.
3. The chemical compound as defined in claim 1 which is dicyclopropyl cyclopropane phosphonate.
4. The chemical compounds as defined in claim 1 which is dicyclopropyl phenyl phosphate.

5. The chemical compound as defined in claim 1 which is dicyclopropyl benzene phosphonate.
6. The chemical compound as defined in claim 1 which is dicyclopropyl tolyl phosphate.
7. The chemical compound as defined in claim 1 which is dicyclopropyl toluene phosphonate.
8. The chemical compound as defined in claim 1 which is monocyclopropyl diphenyl phosphate.
9. The chemical compound as defined in claim 1 which is monocyclopropyl phenyl benzene phosphonate.
10. The chemical compound as defined in claim 1 which is monocyclopropyl ditolyl phosphate.
11. The chemical compound as defined in claim 1 which is monocyclopropyl tolyl toluene phosphonate.
12. The chemical compound as defined in claim 1 which is monocyclopropyl tolyl phenyl phosphate.

13. The chemical compound as defined in claim 1 which is monocyclopropyl tolyl benzene phosphonate.
14. The chemical compound as defined in claim 1 which is monocyclopropyl phenyl toluene phosphonate.
